(57) **CLAIM**

The ornamental design for a vehicle engine cover, as shown and described.

DESCRIPTION

FIG. 1 is a rear, bottom and right perspective view of a vehicle engine cover, the drawing being lined to indicate a transparent material, embodying our new design;

FIG. 2 is a rear, top and left perspective view thereof;

FIG. 3 is a rear, bottom and right perspective view thereof;

FIG. 4 is a front, bottom and right perspective view thereof;

FIG. 5 is a rear, top and right perspective view thereof;

FIG. 6 is a bottom plan view thereof;

FIG. 7 is a top plan view thereof;

FIG. 8 is a rear elevation view thereof;

FIG. 9 is a front elevation view thereof;

FIG. 10 is a left side elevation view thereof; and

FIG. 11 is a right side elevation view thereof.

FIG. 12 is a rear, bottom and right perspective view of a second embodiment of a vehicle engine cover, the drawing being lined to indicate a translucent material, embodying our new design;

FIG. 13 is a rear, top and left perspective view thereof;

FIG. 14 is a rear, bottom and right perspective view thereof;

FIG. 15 is a front, bottom and right perspective view thereof;

FIG. 16 is a rear, top and right perspective view thereof;

FIG. 17 is a bottom plan view thereof;

FIG. 18 is a top plan view thereof;

FIG. 19 is a rear elevation view thereof;

FIG. 20 is a front elevation view thereof;

FIG. 21 is a left side elevation view thereof; and,

FIG. 22 is a right side elevation view thereof.
